UNITED STATES PATENT OFFICE.

GEORGE E. SEIDEL, OF RICHMOND, INDIANA.

ANCHOR-STRAP.

1,299,512.

Specification of Letters Patent.

Patented Apr. 8, 1919.

Application filed August 12, 1918. Serial No. 249,478.

To all whom it may concern:

Be it known that I, GEORGE E. SEIDEL, a citizen of the United States, residing in the city of Richmond, in the county of Wayne, State of Indiana, have invented a new and useful Anchor-Strap, of which the following is a full, clear, and comprehensive specification and exposition, the same being such as will enable others to make and use the same with exactitude.

In loading automobiles, or other vehicles, in or on cars it is important that the vehicle shall be well anchored in order that it may not be jarred or forced out of position in transit, therefore to accomplish this with absolute positiveness and with a minimum amount of time, labor, and expense devoted thereto, and without danger of damage to the vehicle, is the paramount object of this invention.

More specifically stated, my object is to provide anchor-straps which may be previously prepared, and when the vehicle is in position for shipment the anchor straps may be quickly attached to retain the vehicle in position, and then after the vehicle has arrived at its destination the anchors may be quickly removed and again used in the same manner as before.

Other minor objects and particular advantages of the invention will suggest themselves in the course of the following description, and that which is new will be set up in the appended claims.

The preferred form for the construction of my invention, and one manner of its application to practice, is clearly shown in the accompanying drawings, in which—

Figure 1 is a perspective view of a portion of an automobile, showing two of the wheels anchored by means of my invention.

Fig. 2 is an enlarged perspective view of one of my anchor straps alone, showing the relative positions of the parts but with the end portions moved apart, laterally with relation to each other.

And Fig. 3 is an edge view of one of my anchor straps alone, with the end portions shown in actual operative position.

Similar indices denote like parts throughout the three views.

In order that the construction, the operation, and the advantages of my invention may be more fully understood and appreciated, I will now take up a detailed description thereof, in which I will set forth the con-

struction and the operation as fully and as comprehensively as I may.

Referring now to the drawings in detail: Numeral 1 denotes the strap or body portion of the device, this is formed, preferably, of very strong flexible fabric or webbing, having slight elasticity, but which may however be formed of metal or other suitable material if desired.

To the ends of the strap 1 are secured angular metal plates A and B, which are capable of being secured to a floor, and will be hereinafter set forth.

Each of the plates A and B is formed of a single length of flat metal folded upon itself to provide a double thickness thereof, and each plate is bent near the center, after being folded, to form two portions which are disposed at an obtuse angle with relation to each other.

An end of the flexible body or strap 1 is located between the two thicknesses of the plate, from which it projects parallel therewith, and it is secured to the plate by a plurality of rivets C and C', which extend through both thicknesses of the plate and through the strap. The turned edges, D and D', of the plates are located at the end of the plate remote from the strap.

Also an aperture, E and E', is formed through that part of each plate other than that to which the strap is secured, and said apertures extend through both thicknesses of the plate.

The said apertures are so located that they will register with each other when the two plates A and B are nested together, as in Figs. 1 and 3.

Numeral 2 denotes lag-bolts or screws, there being one for each anchor strap, that is one for each two plates, and the body portion of the lag-bolt is adapted to be inserted through the apertures E and E', with the heads of said bolts or screws in contact with the surface of plate B.

Letter X denotes the support, which may be the floor of a car, or the deck timbers above the floor. Letter Z denotes the chock blocks formed to fit the curvature of the wheel and in which the wheel rests, said blocks being located on the floor X; and Y denotes the side-boards which are secured to the sides of the blocks Z and contact with the sides of the tires T which are carried by and form a part of the wheel. Letter W denotes the spokes of the wheels, only those

being lettered which are employed with my anchor.

It is to be understood that the two plates of each anchor strap may, if desired, be secured to the floor independently of each other that is they may be spaced apart, as in Fig. 2, and each may be secured by a lag-bolt.

Operation: The vehicle to be anchored is first placed in position in connection with the chock-blocks, in the usual manner, as shown in Fig. 1. Two of my anchors are then employed with each wheel of the vehicle, the central portion of the body of each anchor is then placed around a spoke, the two anchors for that wheel being located on spokes forward and rearward of a vertical line through the center of the wheel. The end plates of the anchor are then nested together and brought down and outward to the floor, the forward anchor being disposed downward and forward at an angle and the rearward anchor being disposed downward and rearward at an angle. The angle at which the anchors are disposed being governed by the distance required to make the anchors taut after they are secured to the floor.

From the above it is evident that the two anchor straps for any one wheel act as braces counteracting each other and thereby preventing the wheel from being moved forward or rearward, as well as upward. Also it will be observed that the two anchors of one wheel will act as braces counteracting with the two anchors of the wheel directly opposite thereto, thereby preventing lateral or sidewise motion of the vehicle.

The lag-bolt or screw for each anchor is then driven into the floor X, passing through the registering apertures E and E' of the plates of the anchor, the head of the screw or bolt contacting with the surface of the upper plate and rigidly holding the plates in contact with the floor, and as the screws or bolts are tightened down they are caused to pull upon the straps or body of the anchor strap thereby making them taut or under tension.

As the four wheels of the vehicle are thus anchored it is evident that the vehicle will be securely retained in position, yet there will be enough elasticity in the anchor straps

to prevent undue strain, and as the contact portions of the anchor straps with the wheels are of fabric or soft material it is evident that the paint or varnish will not be damaged thereby.

I desire that it be understood that various changes may be made in the form, size, and the proportions of the parts, and in the kind and the character of the material employed, without departing from the spirit of the invention and without sacrificing any of the advantages thereof.

Having now fully shown and described my invention, what I claim and desire to secure by Letters Patent of the United States, is—

1. An anchor strip comprising a strap of flexible material adapted to form a loop with its ends brought near together, an angular plate secured to each end of the flexible material and each having an aperture therethrough, said plates being adapted to be nested together with the said apertures thereof in registering alinement with each other whereby a bolt may be inserted through the apertures to secure the plates to a floor.

2. In combination with a vehicle having wheels a pair of anchor straps for each wheel and each comprising a strip of slightly resilient and flexible material whose central portion may be looped in connection with a portion of a wheel with its ends extending toward the support for the vehicle, an angular plate secured to each of said strips, each of said plates having portions at obtuse angles to each other with the portion farthest from said strip adapted to rest flat upon the support for said vehicle, the two plates of each anchor strap being adapted to nest together one upon the other, and a single securing means for detachably connecting two of the nested plates to said support, all substantially as shown and described.

In testimony whereof I have hereunto subscribed my name to this specification in the presence of two subscribing witnesses.

GEORGE E. SEIDEL.
